Des. 343

Elihu Smith of Albany, N. Y.
Letters Patent No. 343, dated Jan. 17, 1851.

The Schedule referred to in these Letters Patent and making part of the same.

Be it known, that I, Elihu Smith of the City of Albany and State of New York, have produced a new ornamental Design for a Parlor Stove, which stove is known as Smith's Mirror Stove.

And I declare that the annexed drawings are full and accurate delineations of the ornamental parts, with their several ornaments; the end plate not represented, being similar to the one represented, and where portions of the plates are shown, the portions not shown being symmetrical with them and similarly ornamented.

Plate 1 is a perspective elevation of the stove, showing the position of the ornamented plates.

Plate 2-Fig. 1, is a view of the half of mirror stand, with mirror frame.

Fig. 2 is a view of the half of the front plate of the body of the stove.

Fig. 3 is a view of the half of the top plate of the stove.

Fig. 4 is a view of the half of the end plate.

of the Stove.

What I claim as my production, and desire to secure by Letters Patent, is the combination and arrangement of ornamental figures and forms represented in the accompanying drawing, forming together, an ornamental Design for a Parlor Stove.
